LOCK KEY

Leo E. Deutsch, Hammond, Ind.

Application June 25, 1934, Serial No. 732,345

6 Claims. (Cl. 70—9)

The invention relates to a lock key and more especially to a permutation key for locks of permutation kind.

The primary object of the invention is the provision of a key of this character, wherein the permutation parts are confined within the body of the key and are automatically operated for the setting of the permutation mechanism to effect the locking and unlocking of a permutation lock of a construction forming the subject matter of an application for United States Letters Patent filed June 25, 1934 and serially numbered 732,344.

Another object of the invention is the provision of a key of this character, wherein the permutation mechanism is readily changeable through the use of an implement manually actuated and without requiring the removal of any parts of the mechanism from the key, so that said mechanism can be set in conformity with the permutation mechanism of the lock for the actuation thereof in the use of the key, it being obvious that in the event of the loss of a key of this kind, another key of the same type may be borrowed from its possessor and the permutation mechanism thereof altered or changed in conformity with the setting of the lost key and thus enabling a lock to be operated as controlled by the lost key and thereafter such borrowed key can be further altered or changed before return to the rightful owner thereof, and thereby avoiding any possibility of recognition of the true combination of the lock operable by such lost key.

A still further object of the invention is the provision of a key of this character, wherein an unlimited variation of combinations can be had and the changing from one combination to the other is obtainable with dispatch and without dismantling the key and its mechanism contained within the body thereof, the permutation mechanism of the key being automatically set to the combination of a lock for the operation of the latter in the use of the key.

A still further object of the invention is the provision of a key of this kind, wherein the permutation mechanism includes parts which are silent in movement and are slidably arranged within the body of the key, thus there being no liability of derangement or irregularity in the working of the key, that is to say, in the actuation of its permutation mechanism.

A still further object of the invention is the provision of a key of this character which is extremely simple in construction, thoroughly reliable and effective in its purpose, compact, strong, durable,

automatic in its working under the permutation mechanism thereof, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a perspective view of a permutation key constructed in accordance with the invention.

Figure 2 is a top plan view.

Figure 3 is a sectional view on the line 3—3 of Figure 2.

Figure 4 is a transverse sectional view through the key.

Figure 5 is a sectional view on the line 5—5 of Figure 3.

Figure 6 is a fragmentary sectional view through a lock constituting the subject matter of an application for United States Letters Patent serially numbered 732,344 and showing the key inserted within the lock for its actuation.

Figure 7 is an enlarged end view of the key.

Figure 8 is an enlarged vertical transverse sectional view through the key, taken on the line 8—8 of Figure 4.

Figure 9 is a sectional view on the line 9—9 of Figure 4.

Figure 10 is a perspective view of the actuator slide of the key.

Figure 11 is a fragmentary perspective view of one of the tumblers of the permutation mechanism of the key.

Figure 12 is a fragmentary perspective view of the operating plunger for the automatic action of the permutation mechanism of the key.

Similar reference characters indicate corresponding parts throughout the several views in the drawings.

Referring to the drawings in detail, the key comprises a two-part body 10, preferably longitudinally separable, and these two parts are interfitting with each other and held connected by a rivet or fastener 11 passed transversely through the head end 12 of said key. The bit end 13 of the key body has a pair of rows of spaced holes 14 communicating with a chamber 15 within the body 10 and adapted to be projected through these holes 14 is a series of tumblers 16, these being arranged in groups at opposite sides of an actuator slide 17 working within the chamber 15 in the body 10. Each tumbler 16 carries

a segment 18 alternately engageable by the turning of the tumbler with notches 19 and 20, respectively, in the said slide and inner faces of the body 10.

5. Each tumbler, at its outer end, is formed with a wrench-engaging socket or an implement-receiving socket 21 for the turning of said tumbler to change the position of the segment 18 either engaged with the slide 17 or with the body 10
10 of the key and thus controlling the actuation of such tumbler. A suitable wrench or implement is engaged in the socket 21 for the turning of the respective tumblers in the key and thereby
15 altering the permutation or combination of the key.

The slide 17 has connected with it a coiled retractile spring 22 which is also attached internally of the body 10 and this spring functions to normally hold the slide retracted within the body 10 of the key for maintaining said slide under tension.

Pivoted within the chamber 15 inwardly of the slide 17 when in normal retracted position is an actuator cam 23, it being operated upon by an actuator plunger 24 slidably fitted within the body 10 and exposed through the opening 25 in the bit end of the key. This plunger is operated upon by an abutment 26 within the keyway 27 in the turning barrel 28 of the lock 29, the latter constituting the subject matter of an application for United States Letters Patent serially numbered 732,344, so that the said plunger 24 will be shifted to operate the slide 17 which controls the projecting of selected tumblers 16 beyond the bit end 13 of the key and these projected tumblers cooperate with actuators 30 of the permutation mechanism of the lock 29 for the operation of said lock.

Arranged between the rows of tumblers 16 and active upon flat faced portions 31 of said tumblers are retainers 32 to hold the respective tumblers 16 when turned to change the position of the segments 18 upon the tumblers and these retainers are tensioned through a zigzag-shaped spring 33 interposed between the retainers, as is clearly shown in Figure 9 of the drawings. Thus it should be apparent that the tumblers 16 cannot become accidentally deranged when the same have been turned manually for the alteration or changing of the permutation of the key.

The spring 22 connected with the slide 17 operates to return the permutation parts of the key to normalcy when the said key is removed from the lock 29 and this should be apparent.

55. The key, by reason of the arrangement and construction of the permutation mechanism thereof, assures easy alteration or changing of the permutation of said key and the combination or permutation parts can be readily actuated manually for the changing feature without requiring a disassembling of the parts or the separation of the two sections of the body 10 of the key.

65. The permutation mechanism operates silently within the body 10 of the key and it is impossible to detect by sound the action characteristics of the permutation mechanism, so that an unauthorized user of the key can gain knowledge audibly of the set-up of the combination of the key.

70. It will be noted that when the tumblers 16 of the groups or rows have been selectively turned to engage with the slide 17, these selected tumblers are the actuating ones for the permutation

mechanism of the lock 29 for the operation of the same.

The plunger 24 is in the prime mover of the permutation mechanism of the key and the same is automatically moved by the abutment 26 within the lock 29, this abutment being disposed in the path of the plunger 24 when the key is inserted in the keyway 27 in said lock.

What is claimed is:

1. A lock key comprising a body having a bit 10 portion provided with end openings, a plurality of permutation tumblers arranged within the bit portion and adapted for projection through the end openings, means automatically operated on the insertion of the key in a lock to selectively project certain of the tumblers for operation of the lock, and means for effecting the changing of the permutation action of the tumblers.

2. A key of the kind described comprising a body, permutation mechanism confined within the body and alterable at one end of said body without disassembling the body, and an actuator plunger for automatically setting the permutation mechanism within the body on the insertion of the key in a lock.

25. 3. A key of the kind described comprising a body, slideable tumblers fitting within the body, an actuating slide within the body, means on the tumblers for selectively engaging the same with the slide and the body to render certain of the tumblers active and the others passive, and means automatically actuating the slide to move the selected tumblers when the body is inserted in a lock for the operation of the lock by said selected tumblers.

35. 4. A key of the kind described comprising a body, slideable tumblers fitting within the body, an actuating slide within the body, means on the tumblers for selectively engaging the same with the slide and the body to render certain of the tumblers active and the others passive, means automatically actuating the slide to move the selected tumblers when the body is inserted in a lock for the operation of the lock by said selected tumblers, and means within the body and connected with the slide to return said slide and said means to normalcy on extracting the key from a lock.

50. 5. A key of the kind described comprising a body, slideable tumblers fitting within the body, an actuating slide within the body, means on the tumblers for selectively engaging the same with the slide and the body to render certain of the tumblers active and the others passive, means automatically actuating the slide to move the selected tumblers when the body is inserted in a lock for the operation of the lock by said selected tumblers, means within the body and connected with the slide to return said slide and said means to normalcy on extracting the key from a lock, and means within the body to hold the tumblers when adjusted in their selected positions.

55. 6. A key of the kind described comprising a body, slideable tumblers fitting within the body, an actuating slide within the body, means on the tumblers for selectively engaging the same with the slide and the body to render certain of the tumblers active and the others passive, and a plunger slidably fitting the body and active for actuating the slide to advance the tumblers to operative position on the insertion of the body 60 within a lock.

70-411
CERTIFICATE OF CORRECTION.
Patent No. 2,001,601.

May 14, 1935.

LEO E. DEUTSCH.

It is hereby certified that the above numbered patent was erroneously issued to the inventor, said "Deutsch" whereas said patent should have been issued to Marshall William Deutsch, of Hammond, Indiana, as assignee of the entire interest in said invention, as shown by the record of assignments in this office; and that the said Letters Patent should be read with this correction therein that the same may conform to the record of the case in the Patent Office.

Signed and sealed this 26th day of July, A.D. 1938.

(Seal)

Henry Van Arsdale,
Acting Commissioner of Patents.
